UNITED STATES PATENT OFFICE.

CONRAD REGENBOGEN AND PAUL A. RITTER, OF KIEL, GERMANY.

WORKING CYLINDER FOR INTERNAL-COMBUSTION ENGINES.

1,305,494.

Specification of Letters Patent. Patented June 3, 1919.

Application filed May 22, 1915, Serial No. 29,832. Renewed October 25, 1918. Serial No. 259,713.

To all whom it may concern:

Be it known that we, CONRAD REGENBOGEN and PAUL A. RITTER, citizens of the German Empire, residing at Kiel, Germany, have invented certain new and useful Improvements in Working Cylinders for Internal-Combustion Engines, of which the following is a specification.

The present invention relates to an improvement in the working cylinder for internal combustion engines disclosed in patent application Serial No. 808,590 filed December 24, 1913.

In the accompanying drawing, one embodiment of the invention has been shown, the figure illustrating a vertical section of the upper portion of the working cylinder for an upright Diesel motor of large dimensions.

20 The working cylinder consists of an outer cylinder A and an inner cylinder B connected thereto by means of screws D.

In accordance with the invention the portion of the inner cylinder forming the running sleeve for the piston is shown with the cap shaped covering integral therewith. The advantage of this arrangement resides therein that the joint between these two portions is omitted, this joint being very difficult to make tight in large cylinders.

25 The valve F is arranged, similarly to what is the case in the above-named specification, that is to say, the valve F is inserted in the borings formed in the outer cylinder A and the inner cylinder B respectively and the valve gland is threaded in the boring of the inner cylinder B, while it is movable in

the outer cylinder A, so that axial and radial expansion of the inner cylinder will not be prevented by it.

40 If the inner cylinder is produced from steel, a lining of cast iron should be inserted in a well-known manner in its cylindrical portion.

We claim:

45 1. A working cylinder for internal combustion engines having an inner cylinder and an outer cylinder surrounding the same, and means for securing the inner cylinder in the outer one, permitting axial, as well as 50 radial displacement between the two cylinders, said inner cylinder having integral therewith a cap closing one end thereof.

55 2. A working cylinder for internal combustion engines having an inner cylinder and an outer cylinder surrounding the same, and means for securing the inner cylinder in the outer one, permitting axial, as well as radial displacement between the two cylinders, said inner cylinder having integral 60 therewith a cap closing one end thereof, a valve secured in said cap and extending through the wall of said outer cylinder so as to permit displacement between said cap and said outer cylinder.

65 In testimony whereof the foregoing specification is signed in the presence of two witnesses.

CONRAD REGENBOGEN.
PAUL A. RITTER.
